UNITED STATES PATENT OFFICE.

CHARLES W. LORD, OF NEWTON, MASSACHUSETTS.

BILL-FILE.

SPECIFICATION forming part of Letters Patent No. 241,388, dated May 10, 1881.

Application filed March 11, 1881. (No model.)

To all whom it may concern:

Be it known that I, CHARLES W. LORD, a citizen of the United States, residing at Newton, in the county of Middlesex and State of Massachusetts, have invented certain new and useful Improvements in Bill-Files; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

15 The object of this invention is to provide a convenient device for filing bills, letters, receipts, and other documents, which shall be so cheap that it can be filed away with the papers without appreciable loss. To this end I employ a combination of pasteboard guards and lacing tape, cord, or cords, constructed and arranged substantially as hereinafter set forth.

20 In the accompanying drawings, Figure 1 represents a perspective rear view of my improved file. Fig. 2 represents a perspective front view of the same; and Fig. 3 represents a detail cross-section of one of the boards or guards, showing a modified form of eyelet.

25 A designates the rear guard of my file, which 30 consists of a rectangular piece of a thin strip of wood, pasteboard, or other cheap material of similar nature, and which is provided with eyelet-holes 1 2 3 4 5 6 7 8, arranged as follows: Holes 1 and 2 are in the upper part of the 35 guard, in the same horizontal line, and at a little distance apart. Holes 3 and 4 are arranged in a vertical line which would pass through the middle of said space, the upper hole, 40 3, being a little below the horizontal line passing through the holes first mentioned. Holes 45 5 and 6 are arranged in the lower part of the guard, similarly to 1 and 2, and holes 7 and 8 correspond, in like manner, to the holes 3 and 4 of the upper part of the guard. Each quartette of holes, 1 2 3 4 and 5 6 7 8, constitutes a 50 set by itself for the passage of one of the lacing-cords hereinafter mentioned.

B designates the front guard of the file, which is like rear guard A, both in material 55 and form. It has in its upper part two eyelet-holes, 9 and 10, which are opposite holes 1 and 2 of said rear guard, and in its lower

part holes 11 and 12, which are opposite holes 5 and 6 of said rear guard.

C designates the upper lacing-string, and 55 D the lower lacing-string, of the file. The ends of said upper string are first passed backward respectively through holes 9 and 10 of said front guard; then forward around the side edges of said front guard and said rear guard; 60 then backward respectively through holes 1 and 2; then forward together through hole 3; then backward together through hole 4, where they may be tied. Lacing-string D has its ends, in like manner, passed respectively back 65 through holes 11 and 12 of the front guard; thence around the edges of both guards, back severally through holes 5 and 6, and then together through holes 7 and 8.

70 When documents are to be inserted within the file one or both of the lacing-strings may be loosened to allow the requisite expansion of the file, and they are then drawn tight. The guards A and B then protect the rear and front faces of the file of documents, and the lacing- 75 strings C D hold them in line, so that they retain, as a whole, the most convenient shape for pigeon-holing or otherwise stowing away.

75 Of course the method of lacing may be greatly changed. One of the strings may be dispensed with, and the holes made (a single set sufficing) in the middle of the guards; or all the holes can be retained, and a longer lacing-strip used, passing through every one of them. Perhaps the best plan, however, is to use two strings, 85 and carry their ends through to the rear side of the rear guard, A, where they can be most conveniently tied when filing away permanently. All the holes are supplied with eyelets for 90 purposes of protection; but this is not absolutely necessary; nor am I confined to the particular arrangement of holes shown and described, nor to the particular construction of eyelets.

95 As shown in Fig. 3, there may be no openings in the guards, but each may have instead of each eyelet a plate, E, fastened to it by claws e, or in any other convenient manner, this plate having two holes, E', through which the cord passes. Various other forms of eyelet or equivalent devices may be employed.

100 When the file is full it may be stowed away without loss. The boards, strings, and eyelets cost scarcely anything, and will take up

very little room in any repository. Moreover, they make but a slight addition to the weight, and their edges cannot cut anything. Of course their shape may be somewhat changed if desired, though I prefer the one shown.

It will be seen that the use of this sort of file will obviate the necessity for removing and retying the papers, the slipping off of tapes, or else sacrificing something of considerably greater cost. One of these expedients wastes time, the other wastes money. My file saves both.

It will be seen from the position of the cord or tape, as it passes through the eyelets or perforations of the guards, that it is more or less necessarily bound by the edges of said holes, and consequently, after the insertion of a bill or paper, all that is necessary for the clerk to do is to draw the tapes tightly, and the file 20 clamps or holds itself, so that the tiresome act of tying and untying the cords is entirely dispensed with.

When the bills are to be put away permanently then it may be well to tie the guards together for greater security of the papers contained therein.

Obviously there may be many different arrangements in the position of the eyelets and the mode of lacing the guards together without departing from the spirit of my invention. One simple method consists in having but four eyelets in each guard, corresponding to 1, 2, 5, 30 6, and 9, 10, 11, and 12, the cords being passed

outward through 9 and 10 in the front guard B, passing over the outside edges of the guards A and B, then inwardly through the holes 1 and 2, and finally the opposite ends passing upward and outward through 2 and 1, thereby lacing and clamping the upper portions of the two guards A and B. The same may be done 40 with the four lower eyelet-holes, 5, 6, 11, and 12, a little simpler and somewhat cheaper in construction.

Having thus fully described my invention, what I claim as new, and desire to secure by 45 Letters Patent, is—

1. In combination with rear guard, A, having eyelet-holes 1 2 3 4, arranged as described, and front guard, B, having holes 9 and 10, corresponding to 1 and 2, the lacing-cord C, which is passed first through holes 9 10, then round the side edges of the guards, and then successively through holes 1, 2, 3, and 4, substantially as set forth.

2. Lacing-cords C D, in combination with 55 guard A, having eyelet-holes 1 2 3 4 5 6 7 8, and guard B, having eyelet-holes 9 10 11 12, all arranged and combined substantially as hereinbefore set forth.

In testimony whereof I affix my signature in 60 presence of two witnesses.

CHAS. W. LORD.
